REEL

Arthur A. Bureau, Chicago, and Edson M. Denny,
Oak Park, Ill., assignors to Western Electric
Company, Incorporated, New York, N. Y., a
corporation of New York

Application January 8, 1946, Serial No. 639,734

4 Claims. (Cl. 242—123)

1

This invention relates to metal reels and more particularly to a reel having great strength relative to its weight.

An object of the present invention is to provide a sturdy, light reel of simple construction.

In accordance with one embodiment of the invention, a reel is provided having a drum to which is welded, at each end thereof, a metal head comprising a pair of flat annular discs having transversely extending inner and outer peripheral flanges thereon disposed in opposite directions and in telescoping relation with each other and continuously welded to each other and to the drum at their inner periphery and continuously welded to each other at their outer periphery. Fitting within the drum at each end thereof is a supporting cross member comprising a pair of channel members having their flanges disposed in opposite directions and telescoping one pair within the other and welded together and to the drum and being centrally apertured and having a short length of pipe welded therein with its axis concentric with the axis of the reel. In other embodiments of the invention, the outer flanges may be rounded to provide a semi-circular outer portion and reinforcing rings may be fixed in the heads.

The invention will be more fully understood from the following detailed description taken in connection with the drawings, in which

Fig. 1 is an end elevational view of the reel;

Fig. 2 is a side elevational view of the reel shown in Fig. 1;

Fig. 3 is an enlarged vertical sectional view of a portion of the reel taken on the line 3—3 of Fig. 1;

Figs. 4 to 7, inclusive, are enlarged fragmentary cross sectional views of reel heads showing modified forms of construction; and

Fig. 8 is a cross sectional view of the cross member of the reel taken on the line 8—8 of Fig. 1.

Referring to the drawings, wherein like reference characters designate the same parts throughout the several views, the reel 10 comprises a drum 11, to the ends of which, on the outer periphery thereof, are attached hollow, annular heads 12 and 13. The reel 10 is of metal construction and may be used to support cable or other strand material wound thereon. The drum 11 is made from a metal sheet cut to a predetermined size and formed into cylindrical shape with its ends abutting and welded together, as indicated at 15.

Each of the reel heads 12 and 13 comprises

2

a pair of similarly formed annular, metal, channel-shaped discs 17 and 18 provided with transversely extending inner peripheral flanges 20 and 21 and outer peripheral flanges 22 and 23, respectively. The discs 17 and 18 are preformed and are assembled to form a reel head with the flanges 20 and 22 of the disc 17 extending in an opposite direction to and telescoping between the flanges 21 and 23 of the disc 18. With the discs 17 and 18 arranged in assembled relation, they may be welded together at their outer periphery at their line of juncture, indicated at 25. The reel head is assembled on the drum 11 with the flange 21 of the disc 18 engaging the outer peripheral surface of one end of the drum and with the disc 17 flush with the end thereof. The disc 17 and the flange 20 thereon may be welded to the flange 21 of the disc 18 and to the outer end of the drum 11 by a continuous annular weld, indicated at 26. If desired, the juncture between the disc 18 and the drum 11 on the inner side of the reel head may also be welded, as indicated at 27 (Fig. 3).

At each end thereof, the reel 10 is provided with a supporting or cross member 28 fitting within the inner peripheral surface of the drum 11 (Figs. 1 and 3). The cross members 28 each comprises a pair of channel members 29—30 with curved ends cut to fit within the drum 11. The flanges 31 and 32 of the outer channel members 29 extend inwardly and are adapted to engage in telescoping relation the outwardly extending flanges 33 and 34 of the channel member 30 (Fig. 8). The channel members 29 and 30 of the cross member 28 are suitably secured together, as by welding, along their exposed lines of juncture and are positioned within the drum 11 so that the outside face of the member 28 is flush with the end of the drum and welded thereto at the lines of juncture between the member 28 and the drum 11. To reinforce the connection between the cross member 28 and the drum 11, gusset plates 36, 37, 38 and 39 are welded to the ends of the cross member 28 and the drum 11. At its center, the member 28, which extends diametrically across the end of the drum, is provided with apertures 41 and 42 in the channel members 29 and 30 thereof, respectively. The apertures 41 and 42 are concentric with respect to the axis of the drum and are adapted to receive a short length of pipe 44, which is welded to the channel members 29 and 30 and forms a bearing member for a rod or other suitable supporting member on which the reel may be mounted for rotation.

It will be seen that the preferred embodiment

of the reel disclosed in Figs. 1, 2 and 3 is of a simple and rugged construction having parallel double-walled heads formed from annular channel-shaped members, the flanges of which are disposed in opposite directions and nested together in telescoping relation and form a reinforced or double-walled rim and the annular channel-shaped members are secured to each other and to the drum 11 by a continuous weld at their exposed lines of juncture and the reel is provided with hollow reinforced cross members of rectangular cross section, which are provided with tubular bearing members coaxial with the reel.

The rim portion of the reel head formed by the annular flanges 22 and 23 may be further strengthened by the addition of a reinforcing ring 46, as indicated in Fig. 4. The ring 46 may be secured to the flange 22 of the disc 17 before the disc 17 is assembled with the disc 18 by shrinking the disc 17 onto the ring or in any other suitable manner, for example, by welding, after which the discs 17 and 18 may be assembled to form a reel head as previously described.

In the embodiments of the reel heads illustrated in Figs. 5, 6 and 7, the discs 117, 118 and 217, 218, corresponding to the discs 17 and 18 of the heads 12 and 13, are provided with curved outer peripheral flanges instead of flat flanges, as disclosed in the preferred embodiment. The flanges 48 and 49 (Fig. 6) of the annular discs 117 and 118, respectively, are formed to curve outwardly from the plane of the discs on a radius equal to one-half the distance between the discs with the edges thereof engaging in abutting relation. The flanges 48 and 49 of the discs 117 and 118 are welded together where their edges meet to form a continuous weld 50 and the curved flanges form an annular rim having a rounded or semi-circular cross section at its periphery.

An annular member or reinforcing ring 52 (Fig. 5) may be inserted within the head during its fabrication and in engagement with the flanges 48 and 49 and the edges of the flanges 48 and 49 may be bonded together and to the reinforcing ring 52 by a continuous weld 53.

The discs 217 and 218 (Fig. 7) of the reel head may be provided with curved outer peripheral flanges 55 and 56, which, after the discs are assembled, have an overlapping or telescoping relation and may be bonded together by a continuous weld 57.

Although various embodiments of the rim for the reel head have been disclosed, the reel is characterized by having a metal drum with reel heads welded to each end thereof comprising spaced parallel annular discs with inner and outer peripheral flanges contacting and welded to each other.

What is claimed is:

1. A reel comprising a drum and heads on said

drum, each of said heads comprising a pair of similarly formed annular sheets of channel-shaped cross section in abutting relation and welded together at their lines of juncture to provide inner and outer parallel walls.

2. A reel comprising a drum and heads welded to the periphery of the drum at its ends, each of said heads comprising a pair of sheets of metal of annular shape formed to define annular channels with inner and outer peripheral flanges extending equal distances perpendicularly from the web portion of each channel and with the channels open one to the other with their respective flanges engaging each other and welded together at their lines of juncture.

3. A reel comprising a drum and annular hollow heads welded to the drum at each end thereof, each of said heads comprising a pair of similarly formed annular discs arranged in spaced and parallel relation one to the other and having inner and outer cylindrical peripheral flanges extending therefrom and engaging and welded to each other, cross members secured to the inner periphery of the drum at each end thereof, each of said cross members comprising a pair of aligned apertured channel-shaped members nested and bonded together to form a rectangular cross section, and a tubular sleeve member bonded thereto within the apertures in the cross members.

4. A reel comprising a drum and annular hollow heads welded to the drum at each end thereof, each of said heads comprising a pair of similarly formed annular discs arranged in spaced and parallel relation one to the other and having inner and outer cylindrical peripheral flanges extending therefrom and engaging and welded to each other, and cross members secured to the inner periphery of the drum at each end thereof, each of said cross members comprising a pair of aligned apertured channel-shaped members nested and bonded together to form a rectangular cross section.
